UNITED STATES PATENT OFFICE.

MICHEAL J. KERLEY, OF SIOUX CITY, IOWA.

SAFE AND VAULT.

1,427,688.

Specification of Letters Patent. Patented Aug. 29, 1922.

Application filed April 30, 1921. Serial No. 465,646.

To all whom it may concern:

Be it known that I, MICHEAL J. KERLEY, a citizen of the United States of America, and resident of Sioux City, in the county of 5 Woodbury and State of Iowa, have invented certain new and useful Improvements in Safes and Vaults, of which the following is a specification.

This invention relates to safes and vaults 10 and particularly to a safety device applied to the doors of such safes or vaults intended to release a poisonous gas upon the distortion of the locking bar of the safe, as would occur by the use of explosives for dislodging 15 the lock, or the employment of other force, such as hammering or the like, to effect its dislodgment.

An object of this invention is to provide 20 a tank or container for the source of the poisonous gas, whether it be a liquid which, upon evaporation, produces the gas, or whether it is in gaseous form when stored, and means for fracturing the material of the container upon the distortion or dislodgment 25 of the said locking bar, it being, of course, understood that the container is preferably formed of sheet metal or some plastic composition such as earthenware which can be punctured or fractured by the spurs.

30 It is a further object of this invention to provide adjustable fracturing elements in order that their positions with relation to the container or holder may be changed to suit particular requirements and proportions.

35 With the foregoing and other objects in view, the invention consists in the details of construction, and in the arrangement and combination of parts to be hereinafter 40 more fully set forth and claimed.

In describing the invention in detail, reference will be had to the accompanying drawings forming part of this application wherein like characters denote corresponding 45 parts in the several views, and in which—

Figure 1 illustrates a view in elevation of the inner face of a safe door;

Figure 2 illustrates a sectional view on the 50 line 2—2 of Fig. 1;

Figure 3 illustrates a view in elevation of a safe door in a closed position; and

Figure 4 illustrates an enlarged detailed 55 sectional view of a fragment of the locking bar with a spur applied thereto.

In these drawings 5 denotes a safe door which may be of any appropriate construction and is here conventionally shown, having the usual mountings 6 such as hinge members by which it may be supported in 60 place. The door is supplied with the usual lock controlling mechanism such as 7, which may be in the nature of a permutation or time controlling lock which guards a latch or retainer 8 for engaging the locking bar 65 9, the said locking bar being of course connected to the carrier bar 10, by which the locking bolts 11 are projected or retracted, according to the direction of movement imparted to the locking bar, it being understood, of course, that the locking bar may be manipulated by the usual handle, such as 12.

In the present embodiment of the invention, the locking bar is provided with a plurality of spurs or spikes 13, here shown as provided with conical heads terminating in penetrating points, and these heads have threaded shanks 14 adapted to be applied to threaded sockets 15 formed in the inner face 80 or surface of the locking bar. Any convenient number of these spikes or spurs may be employed and I have here shown three which extend approximately the full length of the receptacle 16 which is intended to contain the material which produces the poisonous vapor or gas. The receptacle 16 is secured to the inner surface of the outer wall of the safe door in any appropriate manner, but as the manner of supporting or securing 85 it in its position is an immaterial detail of construction, no mechanical means for effecting this result is illustrated. The threaded shanks 14 have jam nuts 17 applied to them, by which means the spurs may be held at 90 different positions of adjustment, and it is, of course, the purpose of the inventor to have an adjustment of such fineness as to leave the points of the spikes in such close proximity of the wall of the container 16 100 as to cause a puncture or fracture of the wall of the container with but slight movement of the locking bar. This is desirable, because under ordinary conditions of use, the locking bar would not have any lateral 105 movement whatever and therefore, any lateral movement which would be imparted to it, would be caused by unusual conditions which the poisonous vapor or gas would be expected to prevent or stop. Of course, if 110

desired, the points could be set a greater distance from the container, but as this degree of relationship is immaterial to a disclosure of the invention, it will be left wholly to the wishes of the manufacturer or user in practice.

A burglar-proof safe or vault of this character could be produced at comparatively small cost and it could be installed on safes or vaults now in common use, since the only requirement would be the formation of a cavity in the lining of the safe of such size as to receive the container and to form clearance holes to be occupied by the spurs and the shanks. While heretofore I have referred to the manner of retaining the container in place as possibly including a mechanical means, in most instances the lining of the safe would perhaps be relied upon as

a means for holding the container in proper 20 relation to the spurs.

I claim:

1. In a safe or vault door having a locking bar, spurs carried by the locking bar, and a container for a poisonous element located in proximity to the spurs to be fractured by the spurs upon abnormal movement 25 of the locking bar.

2. In a safe or vault door having a locking bar with recesses therein, spurs having 30 shanks anchored in the recesses, the said spurs projecting from the side of the locking bar, and a container for poisonous material located in proximity to the points of the spurs and adapted to be fractured upon 35 abnormal movement of the said spurs.

MICHEAL J. KERLEY.
